COMBINED HANDLE AND BAIL FOR A CADDY OR THE LIKE

Kurt E. Christoffersen, Norwich, Conn., assignor to The
Artistic Wire Products Co. of Conn. Incorporated,
Taftville, Conn., a corporation of Connecticut

Filed Dec. 17, 1962, Ser. No. 72,887

Term of patent 14 years

(Cl. D44—10)

Fig. 1.

Fig. 2.

Fig. 4.

Fig. 3.

Fig. 5.

FIG. 1 is a side elevational view of a combined handle and bail for a caddy or the like embodying my new design.

FIG. 2 is a top view of said combined handle and bail.

FIG. 3 is a bottom view of said combined handle and bail.

FIG. 4 is an end elevational view thereof.

FIG. 5 is a sectional view taken on line 5—5 of FIG. 1.

I claim:

The ornamental design for a combined handle and bail for a caddy or the like, as shown.
